E. S. HINELINE,
STOP MOTION FOR KNITTING MACHINES.
APPLICATION FILED MAR. 20, 1920.

1,375,218.

Patented Apr. 19, 1921.

UNITED STATES PATENT OFFICE.

EDSON S. HINELINE, OF APPONAUG, RHODE ISLAND, ASSIGNOR TO BODELL & CO., OF PROVIDENCE, RHODE ISLAND, A FIRM COMPOSED OF JOSEPH J. BODELL, FREDERICK B. WILCOX, LOUIS C. GERRY, FREDERICK BODELL, HAROLD C. FIELDS, AND ANTONIO LAZO.

STOP-MOTION FOR KNITTING MACHINES.

1,375,218.

Specification of Letters Patent. Patented Apr. 19, 1921.

Application filed March 20, 1920. Serial No. 367,315.

To all whom it may concern:

Be it known that I, EDSON S. HINELINE, a citizen of the United States, and a resident of Apponaug, in the county of Kent and State of Rhode Island, have invented an Improvement in Stop-Motions for Knitting Machines, of which the following description, in connection with the accompanying drawings, is a specification, like characters on the drawings representing like parts.

This invention relates to stop motions and particularly to stop motions for knitting machines.

In order that the principle of my invention may be readily understood, I have disclosed a single embodiment thereof in the accompanying drawing, wherein—

Figure 1 is a plan view of a part of a circular knitting machine having my invention applied thereto;

Fig. 2 is a vertical section upon an enlarged scale of a portion of the structure shown in Fig. 1;

Fig. 3 is a detail in elevation of a portion of the structure shown in Fig. 1;

Fig. 4 is a detail in vertical section showing a part of the electrical connections preferably employed in the practice of my invention; and

Fig. 5 is a similar detail of parts pertaining to such electrical connections.

An important object of my invention is to provide a knitting machine with an emergency device which is preferably a stopping mechanism, operative by reason of an improperly positioned or defective knitting needle. My invention may be embodied in knitting machines of various types and so far as certain features thereof are concerned it may be embodied in so-called straight or so-called circular machines, but preferably and as herein disclosed my invention is embodied in or used in connection with a circular knitting machine for knitting hosiery or other fabrics wherein at times the knitting needles or the cam mechanism is or are rotated and at other times reciprocated relative to each other, as for making the leg, heel, foot and toe of the stocking.

I will disclose my invention as applied to the so-called Banner type of knitting machine shown in United States Letters Patent

No. 933,443, dated September 7, 1909, but I desire it to be understood that my invention is in no wise limited in its application thereto. In such type of machine, the needle cylinder is at times rotated and at times is reciprocated, and the cam ring is stationary, and desirably, but not necessarily, my invention is practised with such an organization of parts.

Referring more particularly to the drawing, the latch ring of a circular knitting machine as of the so-called Banner type is indicated at 1, and the circular series of needles is indicated at 2. Suitably mounted in the latch ring and preferably by pivoting them upon a horizontal pin 3, is a series of yarn fingers or levers 4, 5, 6, 7, 8, by means of which the desired yarns are fed at the proper times to the needles in a manner not herein necessary fully to disclose. Desirably the yarn finger or lever 7 is employed during reciprocating knitting to feed the yarn during the formation and fashioning of the heel and toe and the yarn lever 8 is employed during the knitting of the leg of the stocking. In Fig. 2, I have represented the yarn lever 8 as in action and the yarn lever 7 for the heel and toe as elevated into inactive position.

In accordance with my invention I provide means preferably to intersect and as herein shown to overlie or overlap the path of the needles, but which may in any suitable manner co-act or function with respect to the needle path and in such manner as to constitute an emergency device in the event of needle defect, as, for example, in the case of an improperly elevated needle due to the breaking of a needle butt or other accident preventing the needle from being drawn to the proper point by the knitting cam.

In Fig. 3, I have indicated at 9 the drawing down of the needles through the agency of the knitting cams in a well known manner and have at 10 indicated an improperly elevated needle, such positioning of the needle being due to some needle defect.

In order to cause such improper elevation of a needle and preferably at or in the vicinity of the knitting point, to effect the operation of an emergency device, such for example as the operation of a stopping mechanism of the machine, I preferably provide

the following construction of parts, which I will specifically describe as a preferred embodiment of my invention but to which my invention is not limited.

5 Upon a lateral extension 11 of the latch ring or a horizontal plate secured thereto, I mount a housing 12 having a pin 13 to which is secured a coil spring 14 connected to a screw or pin 15 upon said lateral extension 10 or plate, said spring 14 tending constantly to move the housing 12 toward the right viewing Fig. 1, that is, in a direction away from the circle of needles 2. Such movement of the housing 12 toward the right is 15 prevented at times by reason of an arm or bracket 16 extending from said housing and preferably having in the end thereof an adjustable screw 17, the end 18 whereof is adapted to contact with the heel and toe 20 yarn lever 7 as indicated in Figs. 1 and 2.

When the yarn lever 8 is in operative position as indicated in Fig. 2 to feed yarn to the needles during circular or rotary knitting, the yarn lever 7 for reciprocating knitting is elevated into inactive position as indicated in Fig. 2, and preferably through automatically acting agencies characteristic of the so-called Banner machine. When said yarn lever 7 is in its elevated or inactive 30 position as shown in Fig. 2, it holds the housing 12 in its extreme position to the left as indicated in Fig. 1, but when the yarn lever 8 is elevated into inactive position and the yarn lever 7 is lowered into inactive position, then the screw 17 and arm or bracket 16 are permitted to move toward the right viewing Figs. 1 and 2 through the stress of the spring 14 and the housing 12 and all parts carried thereby are similarly moved 35 40 toward the right viewing Fig. 1 so as to withdraw from functional or active relation with respect to the needles the means employed by me, which, as hereinbefore stated, preferably overlaps the path of the needles 45 during rotary or circular knitting.

Upon the housing 12 a slide or element having a right line movement and indicated at 19 in Fig. 1, is mounted and for that purpose is preferably provided with two slots 50 55 60 65 70 75 80 85 90 95 100 105 110 115 120 125 130 receiving screws 21, 22 extending from the face of the housing, or if desired from an inner surface thereof so that only the end 23 of the element 19 is exposed, the other portion being concealed, if desired, within the housing. Upon a pin or stud 24 that extends from or is within the housing 12 is mounted a lever 25 having an arm 26 provided preferably with two projections 27, 28 adapted to engage a pin 29 upon the element 19, and in the position of said element 19 shown in Fig. 1 to hold said lever 25 in the position shown in said figure. A spring 30 connected at one end to a pin 31 upon the lever 25 and at its other end to the housing 12 or the arm 16 thereof tends to move

the lever 25 in a contraclockwise direction. Such movement is, however, prevented so long as the pin 29 is positioned between the projections 27, 28.

The lever 25 is provided with a second 70 arm 32 having a contact member 33 from which extends a suitable wire 34 forming a part of an electric circuit containing a battery or other source of energy not herein necessary to disclose. Upon or within the 75 housing 12 is provided a second contact 35 from which extends a wire 36 constituting a part of said electric circuit.

Desirably the lever 25 together with the contacts 33, 35 are positioned within the 80 housing so as to prevent all possibility of sparking in an exposed position.

So long as the element 19 is in functioning relation to the path of needles 2 and so long as all the needles function properly, the 85 parts remain in the position indicated in Fig. 1, during rotary knitting. In the event a defective needle 10 remains elevated at or near the knitting point, the said needle engages the element 19 and moves the same in 90 a right line direction and in a path which is substantially or nearly tangent to the circle of needles and so as to withdraw the pin 19 from engagement with the projections 27, 28. Thereupon the spring 30 moves the lever 25 95 so as to complete the circuit by engagement of the contacts 33, 35. Thereupon the machine is stopped or any suitable emergency device is caused to function, such, for example, as an alarm or indicator.

So long as the parts function properly in circular work, the element 19 remains in its overlapping relation with respect to the needle path, but during and for reciprocating knitting, and particularly where a portion of the circle of needles is elevated and remains elevated as in the formation of a heel or toe, the element 19 is moved into non-functioning position and desirably through the co-action of the yarn lever 7, as hereinbefore described.

The element 19, herein represented as a slide, constitutes a catch-releasing element, and one which is adapted to be engaged by a defective needle. Said element is periodically, and desirably for reciprocating knitting for the formation of a heel and toe, moved into non-functioning position.

Having thus described one illustrative embodiment of my invention, I desire it to be understood that although specific terms are employed, they are used in a generic and descriptive sense and not for purposes of limitation, the scope of the invention being set forth in the following claims.

Claims—

1. The combination with the needles of a knitting machine, an emergency device, and a member mounted for sliding movement in a right line, said member having function-

- ing relation with respect to said needles and to be engaged by a defective needle, and thereupon move in a right line, and connections whereby said movement of said member operates said emergency device. 5
2. The combination with a circular series of needles adapted for rotary and reciprocating knitting, an emergency device, a member mounted for sliding movement in a right line, and having functioning relation with respect to said needles during rotary knitting and to be engaged by a defective needle during rotary knitting, and means whereby for and during reciprocating knitting said sliding member is positioned in non-functioning relation with respect to the said circular series of needles. 10
3. The combination with a series of needles, a member mounted for sliding movement in a right line and having functioning relation with respect to said needles and to be engaged by a defective needle, a movable support for said member, and means for periodically moving said support together with said member so that the latter occupies a non-functioning relation with respect to said series of needles. 15
4. The combination with the needles of a knitting machine, an emergency device, a member co-acting therewith and mounted for sliding movement in a path which is substantially in line with the path of movement of a defective needle at its time of engagement with said sliding member, and means whereby such movement of said member operates the emergency device. 20
5. The combination with a circular series of needles, an emergency device, a member coöperating therewith and mounted for movement in a path substantially tangent to said circle of needles, and adapted to be moved in said path by a defective needle, and means whereby such movement of said members operates the emergency device. 25
- 45 6. The combination with the needles of a knitting machine, an electrical stop motion, a member coöperating with said electrical stop motion and having movement in a right line when engaged by a defective needle, and provisions whereby such movement of said member actuates said electrical stop motion. 50
- 55 7. The combination with the needles of a knitting machine, an electrical stop motion, a member having a right line movement when engaged by an improperly elevated needle at or near the knitting point, connections between said member and said electrical stop motion, yarn feeding means, and means whereby said yarn feeding means determines the period of activity of said member. 60
8. A knitting machine having a series of needles, a movable housing or support, an emergency device carried by the latter, a movable member carried by said movable housing or support and adapted to be engaged by and moved by a defective needle, and means for periodically moving said housing or support so as to withdraw said movable member from functioning relation with respect to the needles. 65
- 10 9. A knitting machine having a series of needles, a movable housing or support, an electrical stop motion having contacts carried by said housing or support, a member mounted upon said housing or support and adapted to be moved by an improperly elevated needle, yarn feeding means, and connections between the yarn feeding means and said movable housing and support to move the latter periodically. 70
- 15 10. A circular knitting machine having a circular series of needles 2, a slide 19 adapted to overlie the path of the needles and to be struck and slid by an improperly elevated needle, a movable housing 12 for said slide, electrical contacts 33, 35 carried by said housing, a yarn finger 7, and connections between said yarn finger and the housing to move the latter. 75
- 20 11. A knitting machine having a circular series of needles adapted for rotary and reciprocating work, a slide 19 adapted for movement in a right line and in a path substantially tangent to the circular needles, contact members 33, 35 of an electric circuit of a stop motion, a lever 25 carrying the contact member 33 and having engagement with said slide 19. 80
- 25 12. A knitting machine having a circular series of needles adapted for rotary and reciprocating work, a slide 19 adapted for movement in a right line and in a path substantially tangent to the circular needles, contact members 33, 35 of an electric circuit of a stop motion, a lever 25 carrying the contact member 33 and having engagement with said slide 19, and means for moving said slide into non-functioning relation with respect to the said series of needles for and during reciprocating work. 85
- 30 13. A knitting machine having a circular series of needles 2, a latch ring 1 coöperating therewith, the latter having one or more yarn fingers and also having a movable housing, contacts for an electrical stop motion carried by said housing, a slide 19 also carried by said housing, operative connections between said slide and said contacts, and operative connections between a yarn finger and said housing periodically to move the latter. 90
- 35

In testimony whereof, I have signed my name to this specification.

EDSON S. HINELINE.
